UNITED STATES PATENT OFFICE.

HORACE LEOPOLD TUCKER BUCKLE, OF IVER HEATH, ENGLAND, ASSIGNOR TO VICTOR TALKING MACHINE COMPANY, A CORPORATION OF NEW JERSEY.

AUTOMATIC BRAKE FOR TALKING MACHINES.

Application filed December 28, 1927, Serial No. 243,164, and in Great Britain November 10, 1926.

This invention relates to improvements in automatic brakes for talking machines and in particular to automatic brakes of that type which embody a rotatable braking member, and a detent member adapted to engage said rotatable braking member to hold it in the "off" position and to be moved, by a member moved by or in conjunction with the sound arm, to allow said braking member to move into the "on" position.

The principal object of the invention is to provide an automatic brake of this type wherein the braking member is moved from the "on" position to render the turntable free to rotate, by the manual operation of the soundarm, instead of by the manipulation of a separate brake lever.

A further object of the invention is to provide an automatic brake wherein the braking member is moved from the "on" position by the manual operation of the sound arm and wherein the sound arm, after being moved the distance necessary to set the braking member in the "off" position, may be further moved in the same direction without imposing any strain upon the parts.

According to the invention brake withdrawing means are provided which are adapted to co-operate with the brake member and the soundarm or a member moved by or in conjunction therewith, whereby withdrawal of the braking member from the stopping position may be effected by manual operation of the soundarm.

Co-operation between said brake withdrawing means and the soundarm or member moving in conjunction therewith may be arranged to cease after the braking member has reached the fully "off" position and before the soundarm has reached the limit of its range of movement.

In the preferred form the braking member is moved from the "on" to the "off" position and vice versa alternately by successive movements of the soundarm in one and the same direction.

The invention is illustrated by way of example in the accompanying drawings as applied to an automatic brake for a disc talking machine, the brake being of the kind which is moved into the stopping position by imparting a movement to the sound arm

when the end of the record is reached, in the reverse direction to that in which it moves during playing.

Fig. 1 illustrates the positions of the parts during the playing of the machine.

Fig. 2 the positions when the brake is on and the soundarm has been swung part of the way outwards and the brake is about to be taken off, and

Fig. 3 the positions when the sound box is moved outwards to the position where the needle engages the outer sound line.

The brake comprises a braking member 1 mounted to rotate about a pivot 2 on a base plate 3, said braking member 1 carrying a suitable friction pad 4 which in the "on" position engages the rim of the turntable 5. A two-armed detent member 6 is also pivotally mounted at 19 on the base plate 3 and this detent member 6 is normally urged in a clockwise direction by a spring 7 secured between a lug 8 on said detent member 6 and a lug 9 on the base plate 3.

One end of the detent member 6 engages a trip lever 10 pivotally mounted on the braking member 1 and these two members 6 and 10 are held in engagement by a spring 11 connected between the trip lever 10 and the lug 9 on the base plate 3. This spring 11 also serves to rotate said braking member 1 into the "on" position when the detent 6 is disengaged from the trip lever 10 by rotation of said detent 6 about its pivot in a counter-clockwise direction.

The counter-clockwise movement of the detent 6 is effected by an actuating lever 12 pivotally mounted at 13 on the base plate, said lever 12 being rotated about its pivot 13 by engagement with a post 14 depending from the soundarm 15 to the machine.

A rocking pawl 16 is pivoted at 31 on one end of the actuating lever 12 and is rocked by the engagement of a pin 26 on said pawl with the end 27 of a member 28 arranged over the actuating lever, to rotate therewith and frictionally connected with the pivot 13 in such a manner as to lag slightly behind lever 12 when the direction of movement of the latter is reversed. A pin 25 on the end of pawl 16 away from pin 26 engages in a slot 30 formed in lever 12 to limit the extent of the movement of pawl 16 with regard to lever 12. The pawl

16 slides during the playing of a record over ratchet teeth 17 formed on an arc-shaped part 18 of the end of the detent 6 remote from the braking member 1. When the end of the record is reached a reversal of the direction of movement of the sound arm 15 is effected by suitable means such as by the engagement of the stylus in an eccentric groove formed near the centre of the record and this is attended 5 by a clockwise movement of the actuating lever 12. The pawl 16 is rocked and its end engages and is held against backward movement relatively to the member 18 and a thrust is thereby imparted to the detent 6. The detent 6 is caused to move in a counter-clockwise direction about its pivot 19 and its opposite end is disengaged from the trip lever 10 on the braking member 1 whereby the latter is freed 10 to rotate under the pull of spring 11 into the 20 position where the friction pad 4 engages the turntable rim.

In accordance with the present invention a lever 20 is pivotally connected at one end 21 with the rotatable braking member 1 and is 25 furnished intermediate its length with a slot 22 which engages over a pin 23 upstanding from the base plate 3 whereby said lever 20 is guided during its movements. The end of this slotted lever 20, remote from the braking 30 member 1, is provided with a hook 24 which is adapted to be engaged by the suitably shaped extremity 29 of the actuating lever 12 when a given point in the movement of said actuating lever 12 is reached during the manually effected outward movement of the sound arm 15 (see Fig. 2). Continued movement outwards of the sound arm 15 beyond this given 35 point results in a pull being exerted by the end 24 of the slotted lever 20 as a result of which the braking member 1 is rotated about its pivot 2 into the "off" position (Fig. 3) where it is retained by engagement of the end 40 of the detent member 6 with the trip lever 10 on the braking member 1.

The rotation of the braking member 1 about its pivot 2 causes a combined rocking and sliding movement of the slotted lever 20 with regard to the guide pin 23 in slot 22 and the arrangement is such that when the braking member 1 has reached the "off" position the hook 24 on the end of the slotted lever 20 moves from engagement with the end 29 of actuating lever 12 (see Fig. 3), so that though 50 outward movement of the soundarm 15 is continued, no further pull is exerted by said actuating lever 12 upon the braking member 1 and thus no strain can be imposed upon the parts of the brake.

60 When the brake is actuated to return to the "on" position by the engagement of the pawl 16 on the actuating lever 12 with the teeth 17 on the detent member 6 as above described, the slotted lever 20 moves freely with 65 the braking member 1, being caused, by virtue

of the slot 22 and guide pin 23 to take up a position, where the hook 24 will, during the subsequent manual movement of the sound-arm 15, be engaged by the end 29 of the actuating lever 12.

The duration of the period through which the hook 24 and the end 29 of actuating lever 12 are in engagement to move the braking member 1, may be determined by suitably shaping and positioning the slot 22 in the 75 slotted lever 20 and if necessary one or both sides of the slot 22 may be shaped so that engagement of the shaped portion with the guide pin 23 serves to impart a quick rocking movement of the hooked end 24 of the lever 80 into or out of the path of the end of the actuating lever 12.

What I claim is:

1. An automatic brake for talking machines comprising a rotatable brake member 85 and a detent member adapted to engage said brake member to hold it in the "off" position and to be moved to allow said brake member to move into the "on" position, a sound arm, a member moved by said sound arm, and 90 brake withdrawing means adapted to cooperate with the rotatable brake member and the member moved by the sound arm whereby withdrawal of the brake from the stopping position may be effected by the manual 95 operation of the sound arm.

2. An automatic brake for talking machines comprising a rotatable brake member and a detent member adapted to engage said brake member to hold it in the "off" position 100 and to be moved to allow said brake member to move into the "on" position, a sound arm, a member movable by moving said sound arm in one direction for releasing said detent to allow the brake member to move into the "on" 105 position, and brake withdrawing means adapted to cooperate with the rotatable brake member and the member moved by the sound arm, whereby withdrawal of the brake from the stopping position will be effected 110 by a further operation of the sound arm in the same direction as the movement causing release of the detent.

3. An automatic brake for talking machines comprising a movable brake member, 115 means tending to move the brake member into its "on" position, means for holding the brake member in its "off" position, means for withdrawing the brake member from its "on" position to its "off" position, a sound arm, and 120 connections between the sound arm and the holding means and said withdrawing means so arranged that successive movements of the sound arm in one direction will release the holding means and then operate the brake 125 withdrawing means.

4. An automatic brake for talking machines comprising a movable brake member and a detent member adapted to engage said 130 brake member to hold it in the "off" posi-

- tion, and to be moved to allow said brake member to move into the "on" position, a sound arm, a member moved by said sound arm, and a lever pivotally mounted at one 5 end on the movable brake member and having a hook on the other end adapted to lie in the path of movement of the member moved by the sound arm, when the brake is in the "on" position.
- 10 5. An automatic brake for talking machines comprising a rotatable brake member and a detent member adapted to engage said brake member to hold it in the "off" position and to be moved to allow said brake member 15 to move into the "on" position, a sound arm, a member moved by said sound arm, and brake withdrawing means adapted to cooperate with the rotatable brake member and the member moved by the sound arm whereby 20 withdrawal of the brake from the stopping position may be effected by the manual operation of the sound arm, the cooperation of the brake withdrawing means with the member moved by the sound arm ceasing when the
- brake member reaches the full "off" position, 25 and before the sound arm has reached the limit of its range of movement.
6. An automatic brake for talking machines comprising a movable brake member and a detent member adapted to engage said 30 brake member to hold it in the "off" position, and to be moved to allow said brake member to move into the "on" position, a sound arm, a member moved by said sound arm, and a lever pivotally mounted at one end on the 35 movable brake member and having a hook on the other end adapted to lie in the path of movement of the member moved by the sound arm, when the brake is in the "on" position, and a pivotal guide for said lever so 40 formed that the hooked end of the lever is moved into the path of movement of the member moved by the sound arm when the brake member is "on" and is moved out of said path when the brake member is "off." 45

In testimony whereof I have signed my name to this specification.

HORACE LEOPOLD TUCKER BUCKLE.
